UNITED STATES PATENT OFFICE.

BURTON G. COPE, OF ORRVILLE, OHIO.

LIFTING-JACK.

1,148,890.

Specification of Letters Patent.

Patented Aug. 3, 1915.

Application filed December 19, 1914. Serial No. 878,045.

To all whom it may concern:

Be it known that I, BURTON G. COPE, a citizen of the United States, residing at Orrville, in the county of Wayne and State of Ohio, have invented certain new and useful Improvements in Lifting-Jacks, of which the following is a specification.

My invention relates to improvements in lifting jacks, more especially designed for 10 use in connection with automobiles.

The objects of the present invention are, first, to provide a lifting jack of simple and cheap construction and easily operated; second, to provide a combined actuating lever 15 and supporting base. These objects, together with other objects apparent to those skilled in the art, I attain by the construction illustrated in the accompanying drawing, although my invention may be embodied 20 in a variety of other mechanical forms, the construction illustrated being chosen by way of example.

In the accompanying drawing: Figure 1 is a side view of the jack, showing the same 25 brought into position to hold an axle and wheel in elevation. Fig. 2 is an edge view of a wheel showing the jack in full lines in its initiative position and illustrating in dotted lines different positions, one of the 30 positions being that illustrated in Fig. 1. Fig. 3 is a view of the actuating lever and hub engaging frame, the lever being formed of metal. Fig. 4 is a similar view showing a slight modification of the lever or more 35 particularly a lever formed solid and preferably formed of wood.

Similar numerals of reference indicate corresponding parts in all the figures of the drawing.

40 In the accompanying drawing, 1 represents the hub supporting frame or member which is made up of two spaced bars connected at their hub engaging ends with the integral curved portion or part 2, said portion or part being curved so that it will 45 properly fit the hub of a wheel. The opposite end of the hub supporting frame or member or more specifically the individual bars are pivotally connected to the actuating 50 lever and support 3, a short distance from the base 4 by means of the cross rod or bolt 5 or its equivalent.

In use the lifting jack may be placed in the position shown in Fig. 2, but not necessarily 55 in the exact position but in such a position that when the actuating lever 3 is

brought into a vertical position as illustrated in Fig. 1 the hub supporting member or frame will be elevated a distance substantially equal to the distance between the bottom of the base 4 and the pivotal point of the supporting frame or lever 1. When the lever 3 is brought into this position the portion of the lever above its pivotal point will be substantially parallel with the supporting frame or member 1 and the downward pressure brought upon the supporting frame will be in direct vertical alinement with the lower portion of the actuating lever or more specifically that portion of the elevating lever located below the pivotal point, as between said lever and the supporting element. By this arrangement a suitable base will be provided, owing to the fact that the entire weight will be upon the base 4. 75

In Fig. 4 I have illustrated a slight modification of the actuating lever, but such modification is simply mechanical, as it is also provided with a base 5^a.

It will be understood that the lever 3 80 whether formed as shown in Fig. 3 or formed as shown in Fig. 4 will be free to move between the members constituting the supporting frame and for the purpose of convenience in actuating this lever the members constituting the frame should be spaced a sufficient distance apart to provide clearance for that portion of the actuating lever designed to be operated by the hand, and in order to provide for this advantage the 85 lower portion of the actuating lever should be provided with the engaged or widened portions 6 and 7. In the one instance said widened portion being made up of members and in the other instance formed solid, but 90 regardless of the specific construction of the actuating levers shown the operation is identical and in both instances the weight of the wheel, together with the axle and that portion of the vehicle lifted rests upon the 95 supporting base.

Having fully described my invention, what I claim as new and desire to secure by Letters Patent, is—

In a lifting jack, the combination of an 105 inverted U-shaped supporting frame, an actuating lever consisting of a handle portion and an enlarged base, said base located between the downwardly disposed extremities of said U-shaped supporting frame, and 110 a bolt located through the extremities of the supporting frame and through the enlarged

base of the actuating lever, the handle portion of the actuating lever being of a length less than the distance between the connecting bolt and the hub engaging end of the supporting frame, said handle portion being arranged to lie within said U-shaped frame when the jack is in the raised position.

In testimony that I claim the above, I have hereunto subscribed my name in the presence of two witnesses.

BURTON G. COPE.
